United States Patent Office

Des. 205,424
Patented August 2, 1966

205,424

JAR

James E. Plummer, Toledo, Ohio, assignor to Owens-Illinois, Inc., Toledo, Ohio, a corporation of Ohio

Filed July 22, 1965, Ser. No. 86,252

Term of patent 14 years

(Cl. D58—25)

FIG. 1

FIG. 2

FIGURE 1 is an elevational view of a jar showing my new design;

FIGURE 2 is a top plan view thereof.

The dominant features of my design reside in the portion shown in full lines.

I claim:

The ornamental design for a jar, substantially as shown and described.
